HARNESS MOTION

Carl D. Brown, Hopedale, Mass., assignor to
Draper Corporation, Hopedale, Mass., a corpora-
tion of Maine

Application May 22, 1940, Serial No. 336,614

8 Claims. (Cl. 139—84)

The present invention pertains to shedding devices for looms and more particularly relates to the harness motion of such devices.

Shedding devices of the type to which my invention applies commonly include a plurality of harness frames carrying heddles through which pass the warp threads. These harness frames are usually suspended from the loom arch by harness straps, which are carried over idle guide sheaves on the loom arch and are connected with dobby jacks or bell crank levers arranged adjacent the loom arch. These jacks are caused to oscillate in a plane extending widthwise of the loom, raising and lowering the harness frames. Springs may be attached to the bottom of the harness frames for normally drawing the frames down.

The lift given to the harness frames by the dobby jack is usually a single lift, that is the ratio of movement of the dobby jacks to the movement of the harness frames is 1 to 1, the idle sheaves acting merely as anti-friction rollers. In prior constructions, a large shed opening could be obtained only by making the dobby jacks very long, so that they tend to bend or tilt out of proper alignment and to cramp on their pivotal mounting.

The principal object of the present invention is to provide in a loom having a shedding device of the type above described, a harness motion to give a lift larger than a single lift to the harness frames and means for adjusting the amount of the lift whereby the size of the shed opening produced by the harness frames is adjustable.

The foregoing and other objects may be attained by means of the construction illustrated on the accompanying drawing, of which:

Fig. 1 is a diagrammatic view of the upper arch portion of a loom frame showing one of the operating levers or jacks and the loom harness of my invention associated therewith; and

Fig. 2 is a view to a larger scale taken on line 2—2 of Fig. 1.

In the usual shedding device of a loom at least two harness frames are provided. However, as many more harness frames as are essential to the particular type of weaving being done may be used. Each of the harness frames is usually suspended from the loom arch by a harness structure. The harness structure is connected at one end to the harness frame and extending therefrom passes over sheaves journalled on the loom arch and is connected at its other end to a dobby jack or lever. Means are provided for rocking the dobby jacks back and forth thereby

alternately raising and lowering the frames and forming the shed. Usually means are provided at the bottom of each harness frame to cooperate with the dobby jacks in raising and lowering the frame.

As my invention is directed to the harness for raising and lowering a harness frame, a single harness frame having the harness of my invention is shown and will be described. However, it is to be understood that such harness is applicable to any number of harness frames.

On the accompanying drawing is shown a portion of a loom frame having the arch 1 provided with idle rollers or sheaves 2 and 2', a harness frame 3 suspended beneath the arch and a portion of the dobby mechanism, the jack or lever 4. This jack or lever 4 serves as an illustration broadly of a harness frame actuator movable transversely of the loom to effect the raising and lowering of the harness frame as required in the weaving operation. Cooperating means such as springs 5 may be provided to assist the jack 4 in the raising and lowering of the harness frame 3.

25 A member 6 has a roller sheave 7 journalled in one end and has a loop 8 at the other end thereof. The jack or lever 4 is provided with a plurality of notches 9 for the selective reception of the loop 8, whereby the member 6 may be adjustably attached to jack or lever 4.

The loom arch 1 may consist of a pair of parallel channel bars 10 and 10' secured at their ends to the loom arch ends 11 and 12. Each of the channel bars 10 and 10' is provided with a longitudinally extending slot 13 in the end adjacent the jack 4. A bolt 14 extending transversely of the channel bars 10 and 10' is located in the slots and adjustably secured therein by nuts 15, thus providing longitudinal adjustment of the bolt along the channel bars.

40 A harness is provided for raising and lowering the harness frame, such harness may include a flexible strap 16 connected at one end to a hook 17 in the harness frame 3 and extending therefrom around the sheave or pulley 2. A second flexible strap 18 is connected at one end to the hook 17 in the harness frame 3 and extends therefrom around the sheave or pulley 2'. 45 A third flexible strap 20 extends around the sheave 7 and has a hook 21 on the end of one of its legs for connection to the extended ends of the straps 16 and 18 as at 22. The other leg of strap 20 is provided at its end with fastening means such as hook 24 for attachment to com-

plemental fastening means mounted on the loom frame such as bolt 14.

The bolt 14 may be adjusted within the slots 13 longitudinally of the members 10, 19' and secured in adjusted position by means of nuts 15. This adjustment provides selective increase or decrease of the size of the angle included between the legs of the strap 20 and thereby provides selective adjustment of the ratio of movement of the harness frame to the distance moved by the actuator.

From the foregoing it will be obvious that the shedding device as described will give more than a single lift on the harness and insure a large shed and that the amount of lift is adjustable by changing the location of the member 6 on the jack and by adjusting the bolt 14 in slots 13.

Having disclosed the preferred embodiment of my invention, I claim:

1. In a shedding device for a loom, the combination of a harness frame, an idle sheave, harness strap means attached at one end to said harness frame and extending therefrom around said idle sheave, the other end of said strap means being adjustably connected to a stationary part of the loom, and a harness actuator including a sheave adjustably attached thereto, said sheave engaging said strap means intermediate the ends thereof, the said adjustable connection being adapted to permit the angular relationship of the strap portions extending from said sheave to be selectively varied.

2. In a shedding device for a loom, the combination of a harness frame, a pair of idle sheaves, a pair of harness straps, each of said straps being connected at one end to said harness frame and extending therefrom around one of said idle sheaves, a third strap having one end adjustably connected to a stationary part of the loom and the other end connected to the extended ends of said pair of straps, and a harness frame actuator including a sheave adjustably attached thereto, said adjustable sheave engaging said third strap intermediate its ends, said adjustable connection being adapted to permit the angular relationship of the portions of the said third strap extending from said adjustable sheave to be selectively varied.

3. In a harness motion for looms, the combination with a loom frame, of a harness frame, a pair of idle sheaves journaled on said loom frame, a pair of flexible straps, each of said straps being connected to said harness frame at one end and extending therefrom around one of said idle sheaves, a third strap connected at one end to the extended ends of said pair of straps and having at its other end a hook, a bolt adjustably attached to said loom frame, said hook being detachably hooked on said bolt, a dobby jack provided with a series of notches, a member having a sheave journaled in one end and having a loop at the other end for engaging in one of said notches whereby said sheave is adjustably carried by said jack, said adjustable sheave engaging said third strap intermediate the ends thereof, whereby said jack actuates said harness frame with an adjustable lift.

4. In a harness motion for looms, the combination with a loom frame of a harness frame, strap means attached at one end to said harness frame and adjustably connected to the loom frame at the other end, means carried by said loom frame over which said strap means move, and a harness frame actuator engaging said strap

means intermediate the end thereof adjustably connected to said loom frame and the point of engagement of said strap means with said second named means, the said adjustable connection being adapted to permit the angular relationship of the portions of the strap extending from the harness frame actuator to be selectively varied.

5. In a harness motion for looms, the combination with a loom frame having a slot therein, of a harness frame, a pair of idle rollers journaled on said loom frame, a pair of flexible straps, each of said straps being connected at one end to said harness frame and extending therefrom around one of said idle rollers, a dobby jack having a sheave adjustably connected thereto, a bolt adjustably secured in said slot, a third strap having a hook at one end for detachably engaging said bolt, said third strap extending over said sheave and being attached at its other end to the extended ends of said pair of straps, whereby the ratio of movement of the harness to the distance moved by the jack is greater than one to one and is adjustable.

6. In a shedding device for a loom including a frame, the combination of a harness frame, a pair of idle sheaves, a pair of harness straps, each of said straps being connected at one end to said harness frame and extending therefrom around one of said idle sheaves, a harness frame actuator including a sheave adjustably attached thereto, a third strap passing around said last named sheave and having the end of one leg connected to the extended ends of said pair of straps and the end of the other leg detachably connected to an adjustable member mounted on the loom frame for adjusting the size of the angle included between said legs and means for securing said adjustable member in adjusted position, whereby the ratio of movement of the harness frame to the distance moved by the actuator is greater than one to one and is adjustable.

7. In a shedding device for a loom including a frame, the combination of a harness frame, a pair of idle sheaves, a pair of harness straps, each of said straps being connected at one end to said harness frame and extending therefrom around one of said idle sheaves, a harness frame actuator including a sheave adjustably attached thereto, a third strap extending around said last named sheave and having the end of one leg connected to the extended ends of said pair of straps, fastening means carried by the end of the other leg, complementary fastening means mounted on said loom frame to which said first named fastening means are adapted to be secured, said complementary fastening means being so constructed and arranged as to provide selective increase or decrease of the size of the angle included between said legs, whereby the ratio of movement of the harness frame to the distance moved by the actuator is greater than one to one and is adjustable.

8. A device for selectively varying the amount of movement transmitted from a dobby jack to a harness frame comprising a dobby jack, a sheave adjustably connected thereto, a strap passing around said sheave and having one end secured to a harness strap and the other end secured to means adjustably attached to a loom frame and adapted to permit the angle included between the portions of the strap extending from the sheave to be selectively varied.
